UNITED STATES PATENT OFFICE.

JOHN KREMENEK, OF NAMPA, IDAHO.

REVOLVING TABLE TOP.

Application filed March 17, 1926. Serial No. 95,307.

This invention relates to certain new and useful improvements in revolving table tops and has for one of its objects to provide a table structure embodying a stationary outer table top section with a centrally positioned revoluble smaller table top section so that articles of food or the like placed on the rotatable table top section may be moved to positions in proximity of 5 different points on the stationary table top section to be accessible without the necessity of requiring the passing of foods or the like.

A further object of the invention is to provide a revolving table top for a relatively 15 larger stationary table top section with a plurality of gripping devices to effect rotation of the table top with each gripping device constituting a temporary lock structure for holding the rotatable table top against 20 movement while a person is removing articles of food or the like therefrom, each gripping device being further constructed and designed to indicate when the same is in its table top locking position.

With the above and other objects in view 25 that will appear as the nature of the invention is better understood, the same consists of the novel form, combination and arrangement of parts hereinafter more fully described, shown in the accompanying drawings and claimed.

In the drawings, wherein like reference 30 characters designate corresponding parts throughout the several views,

Figure 1 is a top plan view of the revolving table top constructed in accordance with 35 the present invention,

Figure 2 is a side elevational view of the 40 same,

Figure 3 is a horizontal sectional view taken on line 3—3 of Fig. 2 showing the ball bearing race interposed between the stationary and rotatable table top sections,

Figure 4 is a detail sectional view taken 45 on line 4—4 of Fig. 1 showing one of the gripping and operating devices for the revolving table top section in its upward tensioned position, and

Figure 5 is a detail sectional view, similar 50 to Fig. 4 showing the gripping device in its lowered locked position engaging the stationary table top section to hold the revolving table top section against movement.

Referring more in detail to the accompanying drawings, and particularly to Figs. 1 and 2 there is illustrated a table embody-

ing a standard 1 carried by floor feet 2 and having the usual cross braces 3 at its upper end for supporting a stationary table top section 4.

As shown in Figs. 3, 4 and 5, the stationary table top section 4 is provided with an annular bearing ball race 5 in which bearing balls 6 are freely mounted, while the rotatable table top section 7 positioned centrally of the stationary table section 4 is rotatably retained in position by the pin 8 passing therethrough and anchored in the table section 4 and standard 1. The lower face of the rotatable table top 7 is provided with an annular groove 9 registering with the groove 5 in the table top 4 with the bearing balls 6 working in the opposed grooves as shown in Figs. 4 and 5.

Gripping devices in the form of blocks are carried by the rotatable table top 7 to effect rotation thereof and said blocks cooperate with the stationary table top 4 for holding the rotatable table top against rotation when it is desired to remove foods or the like 75 from the rotatable table top and replace the same, each block when in its table top locking position being retained in a lowered position and having a flat side with a contrasting color that assumes a different position when locked to indicate which block is holding the table top against rotation. As shown in detail in Figs. 4 and 5 the table top 7 is provided with a circular series of 80 spaced openings 10 in which a metallic cylindrical member 11 is mounted with an inwardly directed annular flange 12 at the upper end of the cylindrical member 11. The lower end of said member 11 is internally threaded for the reception of the screw 85 ring 13 for purposes now to appear.

The gripping device or block 14 is of the form and shape best illustrated in Figs. 1, 4 and 5 and has a flattened side 15 of a contrasting color, the block 14 being vertically slidable in the tubular member 11 and having an annular flange 16 engaging the flange 12 upon the tubular member 11. A coil spring 17 is interposed between the block flange 16 and the screw ring 13 for 100 normally holding the block 14 at its limit of upward movement as shown in Fig. 4. The lower end of the block 14 is reduced in stepped formation to provide reduced annular body portions 18 and 19, the lower body portion 19 being moved into a keeper 105 socket in the stationary table top section 4.

to hold the revolving table top section 14 against movement. A circular series of openings 20 is formed in the stationary table top 4 beneath the upper openings 10 and receives a fixed sleeve 21 having a bayonet-shaped slot 22 opening at its upper end, a pin 23 carried by the body portion 19 of the block 14 being moved into the bayonet slot 22 for holding the block in its lowered position and locked to the table top section 4 to prevent rotary movement of the table top section 7. When the block 14 is lowered into its locked position, the same is partially rotated to dispose the flattened differently colored side 15 in another position with respect to the other or remaining upstanding blocks 14 so that it is easily determined which block is lowered for holding the rotatable table top section 7 against movement.

With a rotatable table top of this character, it is possible for persons to have access to a number of dishes of foods, condiments or the like, without the necessity of requiring the passing of such articles, and a table of this character is especially serviceable in a cosmopolitan restaurant where persons of different nationalities dine at the same table and being unfamiliar with different languages, can readily obtain the desired food or article on the table. Should a person fail to release the gripping block

14, other persons seated at the same table can readily tell which block is retaining the table top against rotation and can effect the release thereof.

While there is herein shown and described the preferred embodiment of the present invention, it is, nevertheless to be understood that minor changes may be made therein without departing from the spirit and scope of the invention as claimed.

What is claimed is:—

In a table of the type described, a stationary table top and a revolving table top, means carried by the revolving table top for rotating the same and cooperating with the stationary table top for holding the rotatable table top against movement, said means including a plurality of blocks each having a flattened side of a contrasting color assuming a different position relative to the remaining blocks when in table top locking position, said table tops having a circular series of registering openings therein, a spring in each of the rotatable table top openings for holding the blocks upwardly spaced from the stationary table top and a key and bayonet slot lock carried by each block and the walls of the openings in the stationary table top.

In testimony whereof I affix my signature.

JOHN KREMENEK.
